UNITED STATES PATENT OFFICE.

JOSEPH M. MCKERNAN, OF ST. LOUIS, MISSOURI, ASSIGNOR, BY DIRECT AND MESNE ASSIGNMENTS, OF ONE-HALF TO MAUDE L. MCKERNAN AND ONE-HALF TO LOUISE G. WOLBRINCK, BOTH OF ST. LOUIS, MISSOURI.

SPARK PLUG.

Application filed February 25, 1919. Serial No. 279,184.

To all whom it may concern:

Be it known that I, JOSEPH M. MCKERNAN, a citizen of the United States, residing at St. Louis, in the State of Missouri, have invented certain new and useful Improvements in Spark Plugs; and I do hereby declare the following to be a full, clear, and exact description of the invention, such as will enable others skilled in the art to 10 which it appertains to make and use the same.

This invention relates to a spark plug and particularly to a construction wherein a spark gap is produced within an air tight 15 chamber formed in the plug.

The invention has for an object to produce a novel and improved construction of the cooperating members for effecting the spark gap and involves the provision of a 20 ventilating chamber surrounding the core insulated and completely sealed from the spark gap chamber and also from the electrodes at the inner end of the plug.

A further object of the invention is to 25 provide a novel and improved construction of the spark gap members wherein the spindle telescopes the opposite electrode to effect an automatic adjustment and avoid contact between the spark gap points so that 30 the latter is constant and not liable to accidental displacement.

Another and further object and advantage 35 of the invention is to provide a spark gap chamber formed by the depending portion of the cap which is provided with a conical aperture to receive the cone shaped end of the core carrying the electrode member comprising part of the spark gap construction.

Other and further objects and advantages 40 of the invention will be hereinafter set forth and the novel features therein defined by the appended claims.

In the drawings:

Figure 1 is a side elevation of the plug; 45 Figure 2 a central vertical section thereof; Figure 3 a detail perspective of the cap and cone members; Figure 4 a similar view of the adjustable 50 spark gap cup; and Figure 5 a detail perspective of the gasket ring.

Like numerals refer to like parts in the several figures of the drawings.

The numeral 10 designates the shell or

body of the spark plug which may be of any desired construction and configuration and is provided at its lower end with an exteriorly threaded portion 11 to enter the engine casing and with a spark point or blade 12. The upper portion of this shell 15 is provided with an angular wrench face 13 and interiorly threaded as at 14 to receive the lower threaded portion 15 of the bushing or cap casing 16, which is also provided with a wrench face 17. Within the body 65 of the shell 10 a ventilating chamber 18 is formed which surrounds the body of the core or insulating member 19 disposed within the shell. This chamber is formed with two or more air inlets 20 to draw off the 70 superheated air and permit circulation of cool air around the core 19 which may be formed of any desired insulating material, such as porcelain or other vitreous matter. The shell 10 is also formed with a shoulder 75 or seat 21 at the bottom of the chamber 18 upon which the gasket or packing ring 22 is disposed, and the body of the core 19 is provided with a shoulder 23 adapted to rest upon this ring so as to effect an absolutely gas tight seal between the core and shell.

The gasket 22 is preferably of a special construction comprising the U-shaped metallic retaining ring 24, which embraces the inner 85 circumference of the packing 22, so that when under compression the packing is forced outward therefrom into contact with the side wall of the ventilating chamber 18. This packing 22 is duplicated at the upper 90 portion of the core body where it rests upon a shoulder 25 thereof and is compressed by the inner threaded end of the bushing or cap casing 16. This bushing is adapted to receive the cap insulator 26 which 95 is suitably secured within the upper cylindrical portion thereof, by a binding for instance cement 27. The depending portion 28 of the cap insulator is formed with a conical aperture which completely surrounds and encloses the upper portion 29 of the core from which the electrode or spark point 30 extends. The opposite end of this electrode projects from the lower portion of the core in the usual manner and provides 105 a sparking point 31 disposed opposite and in spaced relation to the point 12.

Mounted in an aperture central of the cap

insulator 26 is the spark gap spindle 32 suitably threaded for purposes to be hereinafter described and at the lower end of this spindle a cup 33 is formed which telescopes the spark point 31 and for that purpose is provided with an interior recess tapering outwardly at its open end as shown at 34. This spindle is also formed with a shoulder 35 to abut against the under face of the cap recess and 5 is adapted to be adjusted by the nut 36 threaded upon the stem 32 to contact with the upper face of the cap. For the purpose of binding an electric conductor in contact with this cap the usual binding nut is provided upon the spindle 32.

The construction and operation of the invention will be apparent from the foregoing description and it will be observed that the location of the ventilating chamber between the upper and lower gaskets to surround the central portion of the core or insulator provides means for withdrawing the superheated air and permitting a circulation of cool air around the porcelain without danger of 20 said air gaining access to the spark gap chamber occupied by the ends of the electrodes. The vent apertures 20 permit any gas escaping past the lower gasket to pass out and not force its passage beyond the 25 upper gasket to enter the spark gap chamber where an explosion would otherwise occur and result in the destruction of the plug. Even the most perfect construction of gasket will at some time leak and the provision 30 of these vent holes absolutely prevents the gas being forced into the spark gap chamber even under the compression pressure from the engine. This is an important feature as no plug with a spark gap chamber 35 can operate successfully if gas is allowed to enter and explode therein, while the provision of a ventilating chamber in this invention renders the plug both safe and efficient.

Experiments have demonstrated that the 40 spark gap chamber must be absolutely air tight and in fact a vacuum is produced therein as the spark consumes the nitrogen and oxygen in the air present in the chamber which requires from 5,000 to 15,000 additional 45 volts to make this arc where it is exposed to atmospheric pressure and this added to the required voltage necessary to produce the spark in the cylinder or combustion chamber under compression, is a severe 50 strain upon the coils and a greater drain 55 upon the batteries which frequently results in short circuiting the coils and destroying the battery. A partial vacuum is produced within the air-tight chamber due to the consumption 60 of certain elements of the air by the arc produced between the adjacent ends of the electrodes so that there is little if any 65 resistance to the formation of the spark and the extra consumption of current is negligible. The use of the vent holes in the ventila-

tion between the gaskets permits the successful application of an air tight spark gap chamber as the entrance of gas thereto is absolutely prevented. The particular construction of gasket herein shown is specially 70 adapted for use in this construction of spark plug as it is held by the retainer permanently in place so that the plug may be disassembled without disturbing the gasket seating and these gasket members are not 75 liable to be misplaced or overlooked in re-assembling the plug.

It will also be seen that the spark gap presented in the present invention occurs entirely within the insulated chamber formed 80 by the recessed cap insulator positioned over the upper end of core 29 carrying the electrode 31, while the opposite electrode is adjustably mounted in the cap insulator and provided with a cup to telescope the upper 85 end of said electrode 31 so that it may be adjusted relative thereto. This forms an automatic spark gap adjustment which avoids jamming the points and provides a spark gap which is constant in its relation. 90 This gap intensifies the firing spark as the core electrode extending into the tapering recess of the spindle forces the current to jump from the sides of the cavity in the spindle to the electrode of the core. This 95 part being enclosed in an absolutely air tight insulated chamber a vacuum is soon established and owing to the absence of atmospheric resistance a greatly intensified spark results. Such a spark tends to highly heat 100 the insulated core which becomes less efficient as the temperature rises, and the ventilating chamber therefore cooperates with the telescopic spark gap to maintain the core at a proper temperature as well as prevent 105 the passage of gas into the spark chamber.

A particular construction and arrangement of the several members of this spark plug have been shown and described but the 110 invention is not specifically confined thereto as changes may be made therein within the scope of the appended claims.

What I claim is:

1. In a spark plug, a shell, an insulating core positioned therein, an electrode seated in said core and projecting beyond the upper end thereof, a bushing removably positioned on the upper end of the shell, a cap insulator carried by said bushing, there being an air-tight chamber formed between the insulating core and said cap insulator, and an electrode carried by said cap insulator and provided at its end within the air-tight chamber with a recess that is adapted to receive the adjacent end of the electrode carried by the insulating core. 115

2. In a spark plug, a shell, an insulating core positioned therein, an electrode seated in said core and projecting beyond the up- 120 125 130

per end thereof, a bushing removably positioned on the upper end of the shell, a cap insulator carried by said bushing, there being an air-tight chamber formed between the insulating core and said cap insulator, and an electrode adjustably carried by the cap insulator, the end of said electrode within the air-tight chamber being constructed so as to partially surround the upwardly 10 projecting end of the electrode carried by said insulating core.

3. In a spark plug, a shell, an insulating core mounted thereon, an electrode extending through and above said core, a bushing

secured to said shell, a cap insulator carried 15 by said bushing and enclosing the upper end of the insulator core carried by the shell, and an electrode mounted in said cap insulator and provided at its lower end with an outwardly tapering recess enclosing the 20 upper end of the core electrode.

In testimony whereof I have signed my name to this specification in the presence of two subscribing witnesses.

JOSEPH M. McKERNAN.
